(57) **CLAIM**

The ornamental design for a tampon wrapper, as shown and described.

DESCRIPTION

FIG. 1 is a front perspective view of a tampon wrapper showing our new design;

FIG. 2 is a rear perspective view of the tampon wrapper of FIG. 1;

FIG. 3 is a front view of the tampon wrapper of FIG. 1;

FIG. 4 is a rear view of the tampon wrapper of FIG. 1;

FIG. 5 is a first side view of the tampon wrapper of FIG. 1; and,

FIG. 6 is a second, opposite side view of the tampon wrapper of FIG. 1.

The broken lines in the drawings illustrating environmental structure or boundaries that form no part of the claimed design.

1 Claim, 4 Drawing Sheets
